UNITED STATES PATENT OFFICE.

NATHANIEL WARSHAW, OF BOSTON, MASSACHUSETTS, ASSIGNOR TO LEWIS-SHEPARD COMPANY, OF WATERTOWN, MASSACHUSETTS, A CORPORATION OF MASSACHUSETTS.

GOVERNING MECHANISM FOR LOAD-HOISTING MACHINES.

Application filed June 21, 1926. Serial No. 117,588.

This invention relates to improvements in load hoisting machines, and the general object thereof is to provide governing mechanism automatically operable by an increase 5 in the speed of the movement of the load beyond a predetermined speed to arrest the movement of the load.

More specifically, the invention relates to governing mechanism for load hoisting machines, such as winches, comprising fluid controlled means for arresting the descent of 10 the load when the speed at which it descends exceeds a predetermined amount.

A further object of the invention is to 15 provide a fluid controlling means of the character above described which is actuated by the rotation of the winding drum of the winch.

A further object of the invention is to 20 provide a fluid controlling device operable by the rotation of the winch drum in excess of a predetermined speed to actuate the braking mechanism of the winch.

A further object of the invention is to 25 provide a simple fluid controlling device of this character which may be applied to the usual types of hoisting machines without material modification of the construction thereof.

30 Other objects and features of the invention will more fully appear from the following description and the accompanying drawings, and will be particularly pointed out in the claims.

35 Inasmuch as the present invention is applicable to the usual type of hoisting machines it is only necessary to show so much of a typical hoisting machine as will illustrate the application of the invention thereto.

40 A preferred embodiment of the invention is illustrated in the accompanying drawings in which

Fig. 1 is a view of a winch actuating and braking mechanism illustrating the present 45 invention applied thereto, cylinders and pistons of the fluid controlled mechanism being shown in vertical section, and portions of the frame also shown in vertical section.

Fig. 2 is a similar front elevation of a 50 similar controlling mechanism, in which a single cylinder and co-operating piston is employed instead of two, as illustrated in Fig. 1.

Preferred embodiments of the invention are illustrated herein as applied to the winch 55 mechanism of a hoisting machine such as that illustrated in the application of Frederick J. Shepard, Jr., and Nathaniel Warshaw, Serial No. 86,820 filed February 8, 1926.

The winch mechanism illustrated herein 60 comprises a rectangular frame having vertical standards 1, which are connected at the lower end by angle bars 2, which may be secured to a suitable base, and at the top by a plate 3, which is welded or otherwise secured to standards 1. The winding drum 4 is fixedly secured to a shaft 5, which is mounted in suitable bearings in the standards 1, and a cable 6, extends from the 65 winding drum upwardly over a sheave (not shown) and is connected at its opposite end to a suitable load supporting means, such as the platform of a hoisting machine. A gear 7, which is secured to the winding drum or its shaft engages a pinion 8, upon a driving shaft 9, which is journaled in the standards 1, and is provided with an angular end portion adapted to be detachably engaged by the 70 usual operating crank (not shown).

Any suitable braking mechanism may be 75 employed. As illustrated herein the braking mechanism comprises a brake drum 10, having a hub which is rotatably mounted upon the driving shaft 9, and is engaged by 80 semi-circular brake bands 11, 12, which are provided at the upper ends with brackets 13, 14, which are secured together by a bolt 15, the brackets being held in spaced relation by a spiral spring 16. The lower ends of the 85 90 brake bands 11, 12 are connected to suitable brake applying levers, as will hereinafter more fully appear.

The brake drum 10 is provided with a flange 17, which is adapted to be detachably 95 connected to the shaft 9, by suitable clutch mechanism, which as illustrated herein comprises a plurality of pivotally connected brake shoes 18, 19, 20. The adjacent ends of the brake shoes 18, 20, are pivotally connected respectively to toggle links 21, 22, the knuckle joint, 23, of which is connected by a link 24, to an arm 25, which is fixedly secured to the shaft.

The brake bands 11, 12, are normally applied to the flange 17, of the brake drum, and 100 105

prevent rotation of the drum. In the winding up of the winch drum the rotation of the driving shaft 9, in a clockwise direction causes the arm 25, and link 24, to draw the toggle links 21, 22, toward the shaft 9, thereby releasing the clutch shoes 18, 19, 20, from engagement with the drum, and permitting free rotation of the driving shaft. Upon completion of the winding up movement a slight counter clockwise rotation of the driving shaft causes the arm 25, and link 24, to expand the toggle and to apply the brake shoes to the brake drum, thereby preventing reverse rotation of the winding drum.

15 The brake applying and actuating mechanism comprises two bell crank levers 26, 27, which are respectively pivotally mounted upon studs 28, 29, extending from one of the vertical standards. The vertical arms 20 of the bell crank levers 26, 27, are pivotally connected respectively to the lower ends of the brake bands 11, 12. The horizontal arm of the bell crank lever 26, is provided with a pin 30, which is engaged by a bifurcated end 31, of the horizontal extension of the bell crank lever 27. The other horizontal arm 32, of the bell crank lever 27, is provided with a spheroidal head 33, which is apertured to receive a vertical rod 34, the lower end portion of which is slidably mounted in a bracket 35, which is secured to standard 1. The spheroidal head of the horizontal arm 32 of the bell crank lever engages a collar 36, which is secured to the rod 34, and rests upon the end of a spiral spring 37, the lower end of which is mounted upon a cross head 38, which rests upon the upper end of a heavier spiral spring 39, which is supported upon the bracket 35.

40 The cross head 38, is connected by a pair of links 40, (one of which is shown) to a bifurcated end 42, of an arm 43, which is fixedly secured to a stud shaft 44, having an angular end portion adapted to be engaged by the operating crank.

In order to release the brake and thereby permit reverse rotation of the winding drum to lower the load, a crank is applied to the head of the stud shaft 44, and rotated in a counter clockwise direction. Such rotation of the shaft depresses the arm 43, and through the links 40 depresses the cross head 38, against the force of the spring 39, thereby relieving the pressure which acts through spring 37 upon the arm 32, of the brake applying lever 27, and through it upon the brake applying lever 26, so that the brake bands are released from effective engagement with the brake drum, thereby permitting reverse rotation of the driving shaft and winding drum.

The mechanism above described is disclosed in the prior application of Shepard and Warshaw, above identified.

45 While a hand-operated mechanism for

rotating the winch drum is illustrated and described herein, it is obvious that suitable power mechanism may be employed for rotating the driving shaft, such for example as an electric motor mounted upon the top plate 3, of the frame, or any other suitable place, and connected to the driving shaft by suitable power transmitting means.

The present invention relates to the provision of automatically operable means 75 adapted to be actuated to arrest the rotation of the winding drum when rotation thereof exceeds a predetermined speed, and thereby to prevent the lowering of the load at an undesirable or dangerous rate of speed. 80

The invention more particularly relates to fluid control governing means which will be ineffective during normal speeds of rotation of the winding drum, or descent of the load, but which will become effective to 85 arrest the descent of the load when a predetermined speed is exceeded.

The mechanism for accomplishing this purpose illustrated herein serves to apply the brake, but it will be obvious that such 90 mechanism may be employed to control other mechanisms.

The particular form of controlling mechanism which is illustrated in Fig. 1 of the drawings comprises a plurality of cylinders 95 45, 46, which are pivotally mounted at the lower ends upon the arm 47, of the brake actuating lever, the other arm 48, of which engages the lower end of the brake actuating rod 34. The brake actuating lever is 100 pivotally mounted upon a stud or fulcrum 49, projecting from the standard 1.

The fluid-containing cylinders 45, 46, are of similar construction, and are respectively provided with tubular pistons 50, 51, having 105 at their upper ends piston rods 52, 53, which are connected respectively to opposite ends of a lever 54, which is fulcrumed at its centre upon stud 55 projecting from the standard 1.

The piston rod 52, is also pivotally connected to an arm 56, of the eccentric strap 57, which embraces an eccentric 58, which is secured to the shaft 5, of the winding drum. 115

The invention in its broad sense contemplates the provision of means for permitting relative reciprocating movement between the piston and cylinder during normal speeds of rotation of the winding drum, 120 or descent of the load, which will not substantially increase the fluid pressure in the pressure chamber of the cylinder, but which will operate to increase the fluid pressure in the cylinder when a predetermined speed of rotation of the winding drum, or descent of the load, is attained, to produce a relative bodily displacement of said cylinder and piston, and the provision of means which is operable by such displacement to 130

apply the brake, or otherwise to arrest the rotation of the winding drum, or the descent of the load.

In the preferred construction illustrated in the drawings the pistons 50, 51, are provided at their lower ends with heads 59, 60, of similar construction, head 59 being shown in section.

The piston head 59, is of substantial thickness, and is provided with an intake port 61, leading from the compression chamber 62, of the cylinder through the piston. The port 61, is provided with a suitable valve such as a ball valve 63, which acts upon the upward movement of the piston to permit the fluid, preferably oil, to flow freely from the chamber of the piston into the compression chamber, but which will, by the closing of the valve upon the downward movement of the piston, prevent the fluid from flowing from the compression chamber through the piston head. The piston head is also provided with a restricted passage which as illustrated herein in its simplest form is a port 64, extending through the piston head, and which is of such cross sectional area as to permit a sufficiently free flow of fluid through it during the reciprocation of the piston at normal speeds as to avoid substantial increase in fluid pressure in the compression chamber of the cylinder. The area of this port, however, is such that when the speed of reciprocation of the piston exceeds a predetermined amount the fluid pressure in the compression chamber of the cylinder will be increased, thereby causing the cylinder to be pressed downwardly against the arm 47, of the brake actuating lever, thus causing the arm 48, to push the brake actuating rod 44 upwardly and through it to actuate the brake applying levers 26, 27, thereby causing the brake bands to grip the brake drum and arrest the rotation of the driving shaft, and through it to arrest the rotation of the winding drum.

Inasmuch as the cylinders 45, 46, are located at different distances from the fulcrum 49, of the brake actuating lever, the port 64, in the head 60, of the piston 51, may be made of such larger diameter than the port 64, of the piston head 63, as to effect a building up of pressure in the compression chamber of the cylinder 46, equal to that which is built up in the compression chamber 62, of the cylinder 45.

In the operation of the device, therefore, the winding up of the cable upon the winch drum will be accomplished by applying the operating crank to the head of the driving shaft 9, and rotating the crank in a clockwise direction. When the load has been elevated to the desired height, release of the winding crank will cause the driving shaft to be rotated slightly in a counter clockwise direction,

thereby applying the brake shoes to the inner face of the flange of the brake drum, it being understood that at this time the brake straps are applied to the brake drum by the actions of the springs 37, 39, upon the brake applying levers 27, 26. Thus the load will be locked in its elevated position. When it is desired to lower the load the operating handle will be applied to the end of the stud shaft 44, and rotated in a counter clockwise direction, thus depressing spring 39, and releasing the pressure applied by it through the spring 37, so that the brake shoes will be gradually released from engagement with the brake drum. This will permit reverse rotation of the winding drum. As the eccentric 58, is secured to shaft 5, of the winding drum, the reverse rotation of the winding drum will act through the eccentric strap to reciprocate the pistons 50, 51, in the cylinders 45, 46, respectively. During normal speeds of rotation of the winding drum the fluid will flow through the piston heads to and from the compression chambers of the respective cylinders with sufficient freedom to avoid the building up of substantial fluid pressure in said compression chambers. However, when the speed of rotation of the winding drum exceeds a predetermined amount the fluid will not be able to pass through the restricted ports 64, in the piston heads with sufficient rapidity to accommodate the rapid reciprocation of the pistons. Therefore, the pressure will be built up in the compression chambers which will force the cylinders bodily downwardly, thereby pushing the arm 47, of the brake actuating lever downwardly and causing the arm 48, to raise the brake applying rod 34, thus causing the brake applying levers 27, 26, to apply the brake bands to the brake so that the rapid descent of the load will be arrested.

In Fig. 2 a similar construction is illustrated, in which a single cylinder 65, is pivotally mounted upon the arm 47, of the brake actuating lever. The piston 66, illustrated in this figure is of the tubular type, and is provided with a head 67, having a valve controlled port 68, to permit the free flow of the liquid therethrough during upward movement of the piston, and to prevent the liquid from flowing therethrough during the downward movement of the piston, and is provided also with a restricted port 69, which acts in the manner above described to avoid the building up of the pressure in the compression chamber of the cylinder during normal speeds of reciprocation of the piston, but to cause the building up of pressure when the piston is reciprocated in excess of a predetermined speed. In this construction the upper end of the tubular piston is connected by upwardly extending arms 70, 71, to the arm

56, of the eccentric strap, as heretofore described. The piston, however, is provided with an external sleeve 72, which slidably fits the outer wall 73, of the cylinder which 5 is shown herein as of somewhat smaller diameter and less thickness than the wall of the compression chamber of the cylinder. The sleeve 72 serves to prevent dust and grit from entering the cylinder and also to 10 prevent splashing of oil from the cylinder. The operation of the mechanism illustrated in Fig. 2 is identical with that shown in Fig. 1, and need not be further described.

It will be obvious that the action of the 15 fluid controlling mechanism in the construction shown in Fig. 2 will be somewhat more intermittent than the duplex controlling mechanism illustrated in Fig. 1, but this construction is somewhat cheaper of manufacture, and is adapted to operate successfully upon lighter duty hoisting machines.

It will be understood that the embodiments of the invention disclosed in the accompanying drawings are illustrative and 25 are not restrictive, and that various changes in form of construction and arrangements of parts may be made within the spirit and scope of the following claims.

It will also be understood that the invention may be embodied in other types of 30 hoisting or lifting machines than those particularly referred to herein.

Having thus described the invention, what is claimed as new, and desired to be secured 35 by Letters Patent, is:

1. Governing mechanism for load hoisting machines comprising a fluid-containing cylinder and piston, means operable by the movement of the load for producing a normal relative reciprocating movement therebetween, means permitting relative bodily displacement of said cylinder and piston, means acting respectively to permit the fluid to flow to and from the compression chamber of the cylinder without substantially increasing the fluid pressure therein during 40 normal relative reciprocating movements of said piston and cylinder, but operable upon increase in such relative movement in excess of a predetermined speed to increase the pressure in said compression chamber, and thereby cause relative bodily displacement of said cylinder and piston, and means operable by such relative bodily displacement 45 to arrest the movement of the load.

2. Governing mechanism for load hoisting machines having a brake comprising a fluid-containing cylinder, a piston reciprocable therein, means permitting relative bodily displacement of said cylinder and piston, means operable by the normal movement of the load to reciprocate said piston, means for permitting the fluid to flow to and from the compression chamber of said cylinder 50 without substantially increasing the pressure

therein during normal speeds of reciprocation of the said piston, but operable upon increase in the speed of reciprocation in excess of predetermined speed to increase the pressure in said compression chamber, 70 and means operable by such increase in pressure to cause relative bodily displacement of said cylinder and piston and means operable thereby to actuate said brake.

3. Governing mechanism for load hoisting 75 machines having a brake, comprising a fluid-containing cylinder connected to and movable with said brake, a piston reciprocable in said cylinder, means operable by the movement of the load for reciprocating said piston, means acting respectively to permit the fluid to flow to and from the compression chamber of said cylinder without substantially increasing the fluid pressure therein during normal speeds of reciprocation of 80 said piston, but operable upon increase in the speed of reciprocation in excess of a predetermined speed to increase the pressure in said compression chamber, thereby causing a bodily movement of said cylinder operable to actuate said brake.

4. Governing mechanism for load hoisting machines having a brake, a brake actuating lever, a plurality of fluid-containing cylinders connected to and movable with said brake actuating lever, pistons in said cylinders, means operable by the movement of the load for reciprocating said pistons in alternating sequence, means acting to permit the fluid in the respective cylinders to flow to and from the compression chambers thereof without substantially increasing the pressure thereon during normal speeds of reciprocation of said piston, but operable upon increase in the speed of reciprocation in excess of a predetermined speed to increase the pressure in the respective cylinders, thereby causing bodily movement of said cylinders operable to actuate said brake.

5. Governing mechanism for winches comprising a fluid-containing cylinder, a piston movably mounted therein, means operable by the rotation of the winding drum to actuate said piston, means normally operable to transmit fluid from one side of the piston to the other without substantially increasing the fluid pressure in the cylinder, but operable upon increase in speed of reciprocation in excess of a predetermined speed to increase the fluid pressure in said cylinder, and means operable by such increased pressure to arrest the rotation of the winding drum.

6. Governing mechanism for winches comprising a fluid-containing cylinder, a piston, reciprocable therein, means operable by the rotation of the winding drum to reciprocate said piston, means permitting fluid to pass through the head of said piston with sufficient freedom at normal speeds of rotation

of the winding drum to avoid substantial increase in pressure in said cylinder, but operable by the rotation of said winding drum in excess of a predetermined speed to increase the fluid pressure in said cylinder, and means operable by such increased pressure to arrest the rotation of said drum.

7. Governing mechanism for winches comprising a fluid-containing cylinder, a piston reciprocable therein having a head provided with a valved port operable to permit fluid to flow freely through said piston head into the pressure chamber of said cylinder, and also provided with a restricted port operable to permit the fluid to flow from said pressure chamber through said head without substantially varying the pressure in said pressure chamber at normal speeds of reciprocation of said piston, but operable to resist the flow of fluid therethrough upon increase in speed of reciprocation in excess of a predetermined speed, means operable by the rotation of said drum to reciprocate said piston, and means operable by increase in pressure in said cylinder to arrest the rotation of the drum.

8. Governing mechanism for winches having a brake and a brake actuating lever comprising a fluid-containing chamber connected to and movable with said brake actuating lever, a piston reciprocable in said cylinder, having a head provided with a valved port permitting a free flow of the fluid into the compression chamber of the cylinder upon upward movement of the piston, but acting to prevent the fluid from flowing therethrough during the downward movement of the piston, and also provided with a restricted port permitting the fluid to flow therethrough without substantially increasing

the pressure in said compression chamber during normal reciprocations of the piston, but operable to increase the pressure in the compression chamber upon increase in speed of reciprocation in excess of the predetermined speed, whereby such increase in pressure will impart bodily movement to said cylinder and thereby cause actuation of the brake, and means including an eccentric mounted upon the shaft of the winding drum for reciprocating said piston.

9. Governing mechanism for winches having a brake and brake actuating lever comprising a plurality of fluid-containing cylinders mounted upon said brake actuating lever, tubular pistons reciprocably mounted in said cylinders, each having a head provided with a valved port acting to permit the fluid to flow freely from the compression chamber of the cylinder through said piston head upon upward movements of the piston, but to prevent flow therethrough during the downward movement thereof, and also provided with a restricted port operable to permit the fluid to flow through the piston head without substantially increasing the pressure in the said compression chamber during normal speeds of movement of the piston, but operable to increase the pressure therein upon increase in the speed of the piston in excess of a predetermined speed, a lever connecting said pistons acting to cause them to reciprocate in alternating sequence, an eccentric mounted on the shaft of the winding drum, and means for causing said eccentric to actuate said lever.

In testimony whereof, I have signed my name to this specification.

NATHANIEL WARSHAW.
